Specification for Design.

Patented Apr. 12, 1921.

Application filed February 14, 1921. Serial No. 445,010. Term of patent 14 years.

To all whom it may concern:

Be it known that I, HENRY B. BROWN, a citizen of the United States, residing at Rochester, in the county of Monroe and State of New York, have invented a new, original, and ornamental Design for Pyrometers, of which the following is a specification and of which the accompanying drawing is a representation.

Figure 1 is a side view of a pyrometer, showing my new design, and

Fig. 2 is a similar view as seen from the right in Fig. 1.

I claim:

The ornamental design for a pyrometer, as shown.

HENRY B. BROWN.
